UNITED STATES PATENT OFFICE.

RENSSELAER BOWKER, OF KOKOMO, INDIANA.

EXCAVATING APPARATUS.

SPECIFICATION forming part of Letters Patent No. 715,962, dated December 16, 1902.

Application filed June 26, 1902. Serial No. 113,308. (No model.)

To all whom it may concern:

Be it known that I, RENNSSELAER BOWKER, a citizen of the United States, residing at Kokomo, county of Howard, State of Indiana, 5 have invented a certain new and useful Improvement in Excavating Apparatus; and I declare the following to be a full, clear, and exact description of the invention, such as will enable others skilled in the art to which it pertains to make and use the same, reference being had to the accompanying drawings, which form a part of this specification.

My invention relates in general to apparatus for excavating, and more particularly to 15 a portable apparatus for digging ditches or making cuts in grading which progresses automatically as the dirt is removed from in front of the apparatus.

Excavating-machines as ordinarily constructed remain stationary while the dirt within a limited radius is being removed and are then propelled forwardly a short distance, so as to bring the apparatus nearer the working point. It is consequently necessary at 25 frequent intervals to interrupt the work of excavating while the apparatus is being propelled to a new working position.

The primary object of my invention is to provide an excavating apparatus which will 30 progress automatically at a speed corresponding to the removal of the earth from in front of the apparatus, and hence render unnecessary any interruption in the work of excavating.

A further object of my invention is to 35 provide an excavating apparatus of the class referred to in which the earth is loosened or broken up and is then automatically removed from the path of the excavator to one or more 40 points, so as to permit a continuous forward movement of the apparatus as the cut or grading progresses.

A still further object of the invention is to 45 provide an excavating apparatus of the type mentioned which will be comparatively simple and durable in construction and efficient in operation.

My invention, generally stated, consists in 50 a portable apparatus comprising means for loosening or breaking the earth, means for then removing the earth to one or both sides of the apparatus, and means for propelling

the apparatus progressively at a speed corresponding to the work of removing the earth.

My invention further consists in one or more 55 augers located at the front end of the apparatus and rotating in transverse planes, conveyer-scoops for removing the dirt as fast as it is loosened by the auger, means for continuously propelling the apparatus, and inter- 60 posed power-transmitting connections whereby the removal of the earth and the propulsion of the apparatus are proportionate to the capacity of the auger.

My invention will be more fully described 65 hereinafter with reference to the accompanying drawings, in which the same is illustrated as embodied in a convenient and practical form, and in which—

Figure 1 is a longitudinal central section of 70 the apparatus on line 1 1, Fig. 3; Fig. 2, an end elevation with the augers removed looking from the right in Figs. 1 and 3; Fig. 3, a sectional plan view of the apparatus on line 3 3, Fig. 1; Fig. 4, a view similar to Fig. 2, 75 showing a modified arrangement of the conveyer; Fig. 5, a detail view of one side of the truck which supports the rear end of the apparatus; Fig. 6, a horizontal section through one of the adjustable supporting-bearings of 80 the front axle, taken on line 6 6, Fig. 7; Fig. 7, an elevational view, partially broken away, of the adjustable bearing illustrated in section in Fig. 6; and Fig. 8 is a perspective view of the adjustable bearing shown in Figs. 6 and 85 7 removed from the frame.

Similar reference characters are used to designate similar parts throughout the several views of the drawings.

Reference characters A A indicate parallel 90 side beams of a supporting-frame upon which the apparatus is mounted.

A', A², and A³ designate cross-beams rigidly connecting the side beams A and A.

The supporting-frame of the apparatus is 95 mounted upon wheels in order that it may be rendered portable. The wheels E' on the axle D' are preferably arranged in two pairs, as clearly indicated in Fig. 3, with a space between each pair for a purpose subsequently 100 to be described. The ends of the axle D' are journaled in axle-boxes d', preferably formed in two vertical portions, secured together in any suitable manner, as shown, for instance,

in Figs. 7 and 8. The axle-boxes d' are vertically adjustable in guides a' , secured to the inner faces of the side frames A A and at correspondingly opposite points. The guides a' 5 may be secured to the side frames A in any suitable manner—as, for instance, by bolts extending through the side frames and also through an interposed filling-block a , fitted between the horizontal portions of the I-beam, 10 of which material the side frames are preferably formed. Suitable means are provided for vertically adjusting the axle-boxes d' within the guides a' , for convenience such means being shown as comprising a screw d^2 , 15 which engages a screw-thread through the top portion a^2 of each guiding-frame and which is provided at one end with means for rotating the same and at its other end with a swiveled connection in engagement with the axle-box d' . By turning the screw d^2 the guides a^2 and side frames A may be elevated or lowered with respect to the axle D'.

The rear end of the supporting-frame is mounted upon a truck D through the medium 25 of a shaft D^2 , which is supported at opposite ends in bearings a^3 a^3 , secured to the inner faces of the side frames A A at correspondingly opposite points. The truck D comprises two similar side frames—such, for instance, as shown in Fig. 5. Each of the side frames consists of upper and lower portions, between the centers of which is a bearing d^2 , through which passes an end of the shaft D^2 . At either side of the bearing d^2 , between the 30 upper and lower portions of each of the side frames, are bearings d^3 and d^4 , in which are journaled the ends of axles D^3 and D^4 . Secured to the axles D^3 and D^4 at opposite ends thereof are wheels E^3 and E^4 , the peripheries 35 of which are preferably provided with transverse grooves to engage ridges projecting from endless tracks which surround each pair of wheels E^3 and E^4 , as clearly illustrated in Fig. 1. One of the end journal-boxes in 40 each of the side frames is longitudinally adjustable, as shown in Fig. 5, for convenience such adjustment being accomplished by a screw-threaded bolt passing through screw-threads in the end d of the side frame and 45 swiveled at one end to the axle-box d^3 .

The endless tracks F, which surround each 50 of the pairs of wheels of the truck D, may be constructed in any desired manner and may preferably consist in a series of metallic sections hinged together, so as to be rendered flexible. The hinges between the several sections of the endless tracks may extend above the inner surface of the endless tracks and 55 constitute transverse projections to engage correspondingly-shaped recesses in the peripheries of the wheels of the truck D.

Mounted upon the supporting-frame are a 60 series of pairs of upwardly-extending beams B B, resting at their lower ends upon the upper faces of the side beams A A, B^2 B^2 , resting at the lower ends upon the cross-beam A^2 , and uprights B^3 B^3 , supported at their

lower ends upon the cross-beam A^3 . Parallel beams C C are supported by the upper ends of the pairs of uprights B, B^2 , and B^3 , 70 while transverse beams C' , C^2 , and C^3 unite the side beams C and C and preferably extend between the upper ends of each of the pairs of uprights B, B^2 , and B^3 .

A platform A⁴ is mounted above the truck 75 D, with its ends supported above the cross-beams A' and A². Upon the platform A⁴ is located a motor for communicating the necessary power for the operation of the apparatus. In the present instance I have shown such motor as consisting in a steam-engine G', which is supplied, through a supply-pipe g, with steam from a boiler G, also mounted upon the platform A⁴. The engine G', which may be of any convenient type, rotates a 80 power-shaft G², on one end of which is a fly-wheel g² and on the other end of which is a belt-pulley g' or other power-transmitting device.

Journaled upon the upper cross-beams C', 85 C², and C³ are series of shafts H', H², and H³, the ends of which are journaled in suitable bearings upon the cross-beams C' and C³. A belt-pulley or other form of power-transmitting device j' is secured to the shaft H² and 90 in vertical alignment with the belt-pulley g'. A sprocket-wheel h² is secured to the shaft H² and communicates power to a shaft K², journaled upon the cross-beams A² and A³, 95 through a sprocket-chain J² and sprocket-wheel j², secured to the shaft K² in vertical alignment with the sprocket-wheel h². The end of the shaft K² opposite the sprocket-wheel J² is provided with a gear-wheel k², which is in mesh with two gear-wheels k' and 100 k³, rigidly secured to shafts K' and K³, journaled upon the cross-beams A² and A³ at either side of the shaft K² and located between the respective pairs of wheels E' on the axle D'. The shafts K' and K³ are extended outwardly beyond the cross-beam A³ 105 and are provided at their ends with earth-cutting devices or augers N' and N³, respectively. The augers N' and N³ are preferably duplicates and may be constructed in any 110 suitable manner. For convenience I have shown each of them comprising a hub N, from which radially project cutting-blades n, 115 preferably two in number, located in planes angularly disposed with relation to each other. 120 Each of the blades n may preferably comprise a series of spikes n' and a flange n², secured to the blades n by suitable fastening means.

Secured to the front end of the shaft H², 125 which is rotatably mounted at the top of the framework, are power-transmitting wheels j³ and j⁴, located adjacent to each other, the former of which is for convenience shown as a sprocket-wheel, while the latter is shown as a 130 chain-wheel having a grooved periphery. A sprocket-chain J³ operatively connects the sprocket-wheel j³ with a sprocket-wheel on the shaft H', while a crossed endless chain J⁴

operatively connects the chain-wheel j^4 with a similar wheel fixed to the shaft H^3 . The shafts H' and H^3 are extended beyond their bearings on the front upper cross-beam C^3 , and each is provided with a pair of sprocket-wheels M' and M^3 , which are rigidly secured to the respective shafts. The pairs of sprocket-wheels M' and M^3 are operatively engaged by endless sprocket-chains, to which are secured scoops or shovels M , thereby constituting conveyers M . The lower ends of the conveyers M are guided upon drums m' and m^3 , loosely mounted upon the shafts K' and K^3 , respectively, between the cross-beam A^3 and the augers N' and N^3 .

A shaft L is journaled at its opposite ends above the cross-beams A' and A^2 and is provided at its forward end with a gear-wheel l^4 , in mesh with a gear-wheel k^4 , secured to the shaft K^2 between an end thereof and the sprocket-wheel j^2 . A worm l surrounds and is secured to the shaft L immediately above the transverse shaft D^2 and engages a worm-wheel l' , secured to said shaft D^2 . A gear-wheel l^2 is secured to the shaft D^2 and is in mesh with a gear-wheel l^3 , fixed upon one of the axles D^4 of the truck D .

Brackets A^5 may be secured to the cross-beam A' , to which may be coupled a tender for carrying the fuel and water for the boiler.

Any slack which may occur in the endless tracks F is removed by adjusting the axle-boxes d^3 within the side frames of the truck D through the adjusting means shown in Fig. 5.

In Fig. 4 I have illustrated a modified arrangement, in which a single conveyer is employed which passes around both of the guiding-drums on the shafts K' and K^3 , but over only one of the pairs of sprocket-wheels M' or M^3 . In this modification all of the dirt is conveyed to one side of the apparatus.

An apron O , preferably made of metal, is located beneath the guide-drums m' and m^3 , and extends outwardly to a point adjacent to the rear of the augers, and is secured to the outer faces of the side beams A . A partition O' extends upwardly at the back of the apron O and serves as a protection for the gear-wheels in the rear thereof. A series of teeth o project outwardly from the lower edge of the apron O and serve to guide loose pieces of dirt into the apron and also to level the portion of the ground between the augers.

The operation of my improved excavating apparatus is as follows: The power-shaft G^2 is rotated by the motor, in the present instance the steam-engine G' , and through the belt J' and belt-wheels g' and j' the shaft H^2 is rotated. The sprocket-chain J^2 and sprocket-wheels h^2 and j^2 , in mesh therewith, communicate rotary motion to the lower shaft K^2 , which in turn, through the meshed gear-wheels k^2 , k' , and k^3 , rotates the shafts K' and K^3 . The augers N' and N^3 , which are rigidly fixed upon the shafts K' and K^3 , are consequently rotated and by their cutting-blades

loosen or break the earth with which they come in contact. Rotary motion is communicated to each of the shafts H' and H^2 by means of the wheels j^3 and j^4 on the shaft H^2 and the chains in engagement therewith, such rotary motion being communicated to the pairs of sprocket-wheels M' and M^3 through their fixed engagement with the shafts H' and H^3 . The conveyers M are consequently moved through their engagement with the pairs of sprocket-wheels M' and M^3 . The lower ends of the conveyers are guided by the loose drums m' and m^3 on the shafts K' and K^3 , so that the scoops m will pass immediately to the rear of the augers and be filled with the loose dirt, which is carried to a point above the sprocket-wheels M' and M^3 , where the inversion of the scoops permits the dirt to fall at either side of the apparatus, preferably into wagons located so as to receive the dirt. The outward inclination of the upright supports B^3 permits the location of the wagons or other conveyances immediately below the points where the scoops are inverted. By means of the meshing gear-wheels k^4 and l^4 rotary motion is transmitted from the shaft K^2 to the shaft L and through the worm l and worm-wheel l^4 to the transverse shaft D^2 , the rotation of which in turn rotates the axle D^4 through the gear-wheels l^2 and l^3 . The pair of wheels E^4 on the axle D^4 is rotated, and through the engagement of the recesses in their peripheries with the ridges or projections of the endless tracks F the rear pair of wheels E^3 is rotated, so that the entire apparatus is propelled simultaneously with the operation of the augers and conveyers.

It should be noted that the sprocket-wheel h^2 is smaller than the sprocket-wheel j^2 , while the power-wheels j^3 and j^4 are larger than the sprocket-wheel h^2 , but of approximately the same size as the power-wheels located upon the shafts H' and H^3 , which drive the conveyers, so that the speed with which the conveyers are moved is much greater than the speed of rotation of the augers N' and N^3 , especially as the gear-wheels k' and k^3 on the shafts K' and K^3 , to which the augers are fixed, are larger than the gear-wheel k^2 , by which they are driven and which is fixed on the shaft K^2 . It should be also noted that the power connection between the shafts L and D^2 , consisting in a worm and worm-wheel, produce a relatively slow rotation of the latter shaft, so that the apparatus is propelled forwardly very slowly compared to the speed of rotation of the augers and conveyers. The relation between the power-transmitting connections should be such that the apparatus will move forwardly only as fast as the augers can cut or loosen the earth and only as fast as the conveyers can remove the same from in front of the apparatus. The depth of the cut may be varied by adjusting the supporting-framework with respect to the front axle D' . If a shallow cut is only desired, the side beams A

are moved vertically upwardly with respect to the axle-boxes d' , while if a deep cut is required the side beams A are moved downwardly relatively to the axle-boxes d' .

5 While it is preferable to employ two conveyers which are so driven as to deliver the dirt at both sides of the apparatus, circumstances may arise which render it expedient to deliver the dirt at only one side, and in 10 such case a single conveyer is employed, which passes around both of the loose guide-drums m' and m^3 and around one of the pairs of sprocket-wheels M' or M^3 . In Fig. 4, for instance, a single conveyer is shown which 15 passes around the pair of sprocket-wheels M' , and hence all of the dirt would be delivered to one side alone of the apparatus.

From the foregoing description it is evident that I have devised an excavating apparatus 20 which will be propelled automatically and continuously as fast as the dirt in front thereof is removed, and consequently no loss of time is incurred in moving forward the apparatus at frequent intervals in order that it 25 may be kept within proper working distance of the earth which is to be removed.

While I have described more or less precisely the details of construction, I do not wish to be understood as limiting myself 30 thereto, as I contemplate changes in form, the proportion of parts, and the substitution of equivalents, as circumstances may suggest or render expedient, without departing from the spirit of my invention.

35 Having now fully described my invention, what I claim as new, and desire to secure by Letters Patent, is—

1. In a portable excavating apparatus, the combination with rotary means for breaking 40 up the earth, of means for removing the broken earth, and means for continuously propelling the apparatus at a speed proportionate to the work of removing the earth, substantially as described.

45 2. In a portable excavating apparatus, the combination with a rotary earth-auger, of a conveyer located adjacent to said auger, and means for continuously propelling the apparatus at a speed proportionate to the work 50 of removing the earth, substantially as described.

3. In a portable excavating apparatus, the combination with a pair of substantially horizontal rotary earth-augers, of endless conveyers adapted to remove the earth from points 55 adjacent to the augers to either side of the apparatus, and means for continuously propelling the apparatus at a speed corresponding to the progress of the work, substantially 60 as described.

4. In an excavating apparatus, the combination with means for breaking up the earth, of an apron located adjacent to said means for receiving the broken earth, and conveyers 65 for removing the earth from said apron, substantially as described.

5. In an excavating apparatus, the combi-

nation with means for breaking up the earth, of an apron located adjacent to said means for receiving the broken earth, conveyers for 70 removing the earth from said apron, and means for propelling the apparatus at a speed proportionate to the work of removing the earth, substantially as described.

6. In a portable excavating apparatus, the combination with a pair of rotary earth-augers, of an apron located adjacent to said augers for receiving the broken earth, and endless conveyers adapted to remove the earth from 80 said apron to the side of the apparatus, substantially as described.

7. In a portable excavating apparatus, the combination with a pair of rotary earth-augers, of an apron located adjacent to said augers for receiving the broken earth, endless 85 conveyers adapted to remove the earth from said apron to the side of the apparatus, and means for propelling the apparatus continuously at a speed corresponding to the work of removing the earth, substantially as de- 90 scribed.

8. In an excavating apparatus, the combination with a supporting-frame, of substantially horizontal rotary means journaled upon said frame for breaking up the earth, a support interposed between said frame and the ground, and connections whereby said frame may be vertically adjustable relatively to its support thereby regulating the depth of the 95 cut, substantially as described.

9. In an excavating apparatus, the combination with a supporting-frame, of longitudinal shafts journaled on said frame, earth-augers fixed upon said shafts, a support interposed between the ground and said frame 105 upon which the latter is mounted, and connections between said support and frame whereby the frame may be raised or lowered to regulate the position of the augers with respect to the surface of the ground, substan- 110 tially as described.

10. In a portable excavating apparatus, the combination with a supporting-frame, of an axle having wheels thereon upon which said frame is mounted, longitudinal shafts journaled on said frame, earth-augers fixed upon said shafts, axle-boxes in which said axle is journaled, and means for vertically adjusting said frame upon the axle-boxes whereby the depth of the cut of the augers is regulated, 115 substantially as described.

11. In a portable excavating apparatus, the combination with a supporting-frame, of means for breaking up the earth mounted upon said frame, an axle having wheels thereon located under said frame at the end thereof adjacent to said means, axle-boxes in which said axle is journaled secured to said frame, a truck comprising side frames and axles journaled therein upon which said supporting-frame is mounted at its other end so as to permit a vertically-swinging motion of said frame, and means for vertically adjusting said frame upon the axle-boxes whereby the depth of the 125 130

cut of the augers may be varied, substantially as described.

12. In a portable excavating apparatus, the combination with a supporting-frame, of 5 wheels upon which said frame is supported, a motor mounted thereon, rotary means for breaking up the earth, means for removing the broken earth, power connections interposed between said motor and each of said means, 10 connections transmitting power from said motor to said wheels for propelling the apparatus, said power connections being so regulated that the apparatus progresses continuously at a speed corresponding to the breaking up 15 and removing of the earth, substantially as described.

13. In a portable excavating apparatus, the combination with a substantially horizontal

rotary earth-auger, of a conveyor located adjacent to and movable in a plane transverse to 20 said auger whereby the earth which is broken up by said auger is removed to the side of the apparatus.

14. In a portable excavating apparatus, the combination with a pair of substantially horizontal rotary earth-augers, of endless conveyors 25 located in planes transverse to said augers and adapted to remove the earth from points adjacent to the augers to either side of the apparatus.

In testimony whereof I sign this specification in the presence of two witnesses.

RENSSELAER BOWKER.
